(Cl. D34—15)

To all whom it may concern:

Be it known that I, Alexander Burkes, a citizen of the United States, residing at New York, in the county of New York and State of New York, have invented a new, original, and ornamental Design for an Inflatable Toy Figure or Similar Article, of which the following is a specification, reference being had to the accompanying drawing, forming part thereof.

In the drawing

Fig. 1 is a top view of an inflatable toy figure or similar article showing my new design;

Fig. 2 is a side elevational view thereof; and
Fig. 3 is a front view thereof.

The essential features of my design are shown in full lines.

I claim:

The ornamental design for an inflatable toy figure or similar article, substantially as shown and described.

ALEXANDER BURKES.
